SHOE AND INNERSOLE AND METHOD OF
PRODUCING THEMWilliam L. Knipe, Haverhill, Mass., assignor to
Knipe Bros. Inc., Haverhill, Mass., a corpora-
tion of Massachusetts

Application September 6, 1943, Serial No. 501,383

7 Claims. (Cl. 36—22)

This invention relates to shoes and innersoles therefor.

The Knipe Patent No. 1,144,420, issued June 29, 1915, discloses an innersole composed of a leather sheet uniformly thin and too thin to be skived or channeled to form a commercially useable sewing lip or rib for attachment to the shoe upper. The sewing lip is provided by a sheet of canvas or other suitable woven fabric, consisting of two canvas or equivalent laminations bonded together and adhesively affixed to the outersole side of the leather sheet except at the margin of its fore and shank part where the margin of the laminated sheet is bent away from the leather sheet to provide the sewing lip. All sheets are further attached together by a line of stitches through the sheets at the base of the sewing lip.

This innersole is more flexible than one made of leather thick enough to have an integral channeled sewing lip and promotes exceptional flexibility of the shoe containing it beyond the normal service requirements.

The leather sheet can be a so-called split and sometimes at least the forepart thereof has adhesively affixed to the inner or exposed face thereof a thin limp higher grade leather sheet constituting a sock lining. Such a composite innersole sometimes shows wrinkles in and transversely of the sock lining when the shoe is flexed, especially beyond its maximum flexure when on the foot.

It is an object of the present invention to reduce the tendency toward wrinkle formation in the flexed innersole constructed as above described and to permit increased bending of a shoe having the innersole without the showing of wrinkles on the inner exposed face of the sock lining.

While the innersole without the sock lining usually is free from objectionable wrinkles when sharply bent about the ball line, there can be, nevertheless, a tendency toward wrinkle formation and it is an object of this invention to reduce this tendency in an innersole construction of the Knipe patent type.

It is also an object of this invention to so arrange the parts of the Knipe patent type of innersole, both with and without the sock lining, that the flexibility and wrinkle-free properties are obtained without tendency to distortion in other directions.

I have discovered that a cause for the wrinkling of the exposed face of the innersole or the sock lining thereof is the fabric sheet and its

distance from the exposed surface. The fabric sheet is inextensible and is fixedly attached to the leather sheet. When the innersole is flexed with the leather sheet in the inside of the curve of flexure, the fabric sheet restrains the leather sheet from shifting its position relatively thereto and hence places the leather sheet under compression so that wrinkles can form in the inner face thereof where the compression is highest.

10 I reduce the tendency toward wrinkling by firmly combining the sock lining with the laminated innersole only while both are flexed, preferably to as great a degree as the shoe having the innersole will be flexed in demonstration. 15 Thus each piece is free to flex without control by any other piece. Such a method of making the innersole constitutes an object of the present invention.

While I can combine firmly all three sheets, 20 that is, the sock lining, the leather sheet, and the fabric sheet while all are flexed or bent, I prefer, when the leather sheet is thin enough and of suitable grade not to wrinkle when combined with the fabric sheet and bent, to combine 25 the leather and fabric sheets by an adhesive and also by stitching while both sheets are flat and to bend the combined sheets for combination with the bent sock lining as the inherent resiliency of the flat combined sheets tends to 30 flatten the sock lining. Thus the composite innersole tends to lie flatter than would otherwise be the case and packing of such innersoles and the lasting thereof is facilitated. Such a procedure is also an object of the invention.

35 A further object is generally to improve upon shoes and innersoles and methods of making them.

In the accompanying drawings:

Fig. 1 is a top plan view of an innersole, without a sock lining, embodying features of the invention;

Fig. 2 is a similar view looking at the under or outersole side of the innersole of Fig. 1;

Fig. 3 is a cross sectional view on the line 3—3 of Fig. 1;

Fig. 4 is a top plan view of an innersole like that of Fig. 1 but having a sock lining at the forepart of the innersole;

Fig. 5 is a side elevation looking at the edge of the innersole of Fig. 4;

Fig. 6 is a cross sectional view on line 6—6 of Fig. 4;

Fig. 7 is a side elevation of a press illustrating 55 how the composite sheets may be combined while

provided with forepart curvature according to the present invention;

Fig. 8 is a perspective of a shoe with a portion broken away to illustrate the wrinkling or puckering interiorly of a shoe embodying a composite innersole made according to prior practices;

Fig. 9 is a similar view of a shoe embodying an innersole made according to the present invention, and showing absence of wrinkles when the shoe is flexed as in use;

Fig. 10 is a cross sectional view through the forepart of a shoe embodying my improved innersole, in the region of the ball line thereof; and

Fig. 11 is a detail cross-sectional view of the right hand portion of Fig. 10, on a larger scale.

Referring to the drawings, the innersole of my invention comprises a thin body sheet 10 which preferably is of leather, although it may be of any other suitably strong and flexible innersole material. It is too thin to be satisfactorily channeled to form a commercially useable upper-attaching lip or rib and has uniform thickness throughout its extent. Hence it is exceptionally flexible as distinguished from leather innersoles which are thick enough to have attaching ribs integral of the leather stock and it can bend without being additionally distorted because of its bent condition by reason of purposely varied thickness in its extent. On the under side of this leather body sheet is secured a backing sheet 12 which comprises two thicknesses of suitable fabric, particularly canvas or duck cemented together as described in the Knipe patent and also cemented to the leather body sheet throughout approximately the full area of the innersole and also stitched as at 14 to the leather body sheet all around the margin of the forepart and through the shank region at the edge of the innersole. The uncemented marginal portion of the backing sheet is turned away from the leather body sheet as at 16 at the stitching to constitute an attaching or sewing lip or rib 16 by which the innersole may be secured to the upper and welt of a shoe.

Some innersoles are incorporated in shoes without a sock lining and some have a sock lining 18 cemented to the forepart of the inner face of the leather sheet 10 concealing the stitches 14, the lining sheet 18 usually being a thin limp leather sheet.

The leather and fabric sheets 10 and 12 preferably are adhesively bonded firmly together while both are flat and free from flexure and are stitched together by the stitching 14 prior to combining with the sock lining 18 when the leather sheet 10 is of such grade and thinness that deleterious wrinkles are absent in its inner face when the shoe having such innersole is flexed in use or in demonstration.

The sock lining is combined with the united leather and fabric sheets 10 and 12 while both the lining sheet and the united sheets are in a curved or bent condition that preferably is the maximum bend of the shoe in demonstration which is considerably greater than the bend of the shoe in service on the foot. The combining is done between cooperatively curved parts or jaws 20 and 22 of a mold having appropriate curvature, the sock lining sheet 18 being innermost of the curve as illustrated in Fig. 7. Any suitable adhesive or bonding agent is employed. It can be applied to the face of the lining sheet in the mold and the bent composite attached sheets 10 and 12 brought in contact therewith or the flat lining sheet may be adhesively applied

to the flat leather sheet 10 and then all placed in the mold before the adhesive has set so that the sheets can shift freely relatively to each other before the adhesive sets. The sheets remain in the mold until the adhesive has set and bonded the sock lining sheet firmly to the leather sheet.

When the innersole is removed from the mold the previously flat-united leather and fabric sheets 10 and 12 tend to re-assume their flat form thereby causing the composite innersole to lie flatter than it would otherwise lie so that packing prior to lasting, and lasting in the shoe, is facilitated.

When lasted flat in a shoe the sock lining is under tension and the tension in the exposed face disappears only when the shoe is bent into the configuration of the mold and the shoe can be bent considerably further in the same direction before the exposed face of the sock lining is placed under sufficient compression by the inextensible fabric sheet 12 to cause the formation of wrinkles.

When the leather sheet 10 is of such character that if combined flat with the canvas sheet, wrinkles could form on its inner face, it alone is combined firmly with the canvas sheet in the mold, remaining therein until the adhesive bonding it to the canvas sheet becomes set. It is then removed from the mold and the stitching 14 put in while the combined sheets are in the somewhat flattened but still prominently curved condition they assume when removed from the mold, the stitching being applied by a sewing machine having a usual presser foot that is short lengthwise of the stitch line. If such a leather sheet is also to have a sock lining therein, the lining preferably is applied as above described after the leather and fabric sheets have been adhesively united in the mold and stitched together.

Both forms of innersole as above described are applied to the bottom of the last in the customary manner, the upper 26 is stitched to the sewing lip 16, surplus edge material at the lip is trimmed off, the usual filler 27 is provided, the out sole 28 is applied and, in general, the shoe is built as heretofore.

When the innersole is applied to the last it is flattened out of its normal somewhat arcuate configuration. Thus the sock lining sheet and also the leather sheet 10 or at least the inner face of the latter, is placed under tension while the fabric sheet tends to be compressed. Any shortening of the length of the fabric sheet under compression is absorbed by a loosening of the weave of the fabric between the high surface parts of the weave bonded adhesively to the leather sheet without formation of wrinkles although presence of wrinkles in the fabric sheet in the shoe is not harmful. Flexing of the shoe merely takes up the looseness of weave without opposition to flexure up to the degree of bend provided by the mold. Increase of bend beyond this amount is resisted by the fabric. The tensioned condition of the inner face of the leather sheet, and of the sock lining, result in a particularly smooth appearance thereof in the unflexed shoe.

The use of a thin leather sheet 10 reduces the tendency toward wrinkle formation since by the use of such a thin sheet the inner face thereof and the line of the fabric sheet are close together so that the leverage of the fabric sheet on the inner face is small. A leather sheet that is uniformly thin throughout, that is to say, is

free from localized depressions or protuberances, has uniform action under flexure throughout permitting easy extreme wrinkle-free flexure free from tendency toward unwanted distortion.

The mold in which the laminations of the innersole are compressed can be of any type holding the laminations close together under substantial pressure until the adhesive has set. The mold can have cooperating jaws that are separated and brought upon the innersole by mechanical elements or one of the jaws can be an inflatable bag of the general type common in the shoe art.

I claim:

1. The improvement in innersoles which comprises firmly affixing a flat leather sheet of innersole configuration that is uniformly thin and too thin to be channeled to form a useable sewing lip to a flat fabric sheet also of sole configuration having a marginal portion in the fore and shank parts of the sole upturned to provide a sewing lip, stitching the flat sheets together by a line of stitching connecting both sheets at the base of the sewing lip, bending the flat combined sheets out of their flat plane and into a curve which exists at least in the fore part of the innersole and with the inner face of the leather sheet on the inside of the curve, and firmly affixing a thin sock lining sheet to the fore part of the leather sheet while both are in curved condition with the sock lining sheet being innermost of the curve and over the stitches.

2. An innersole comprising a leather sheet of sole configuration too thin to be channeled to form a sewing rib thereof, a fabric sheet of sole configuration adhesively affixed to the thin leather sheet and having a free marginal portion outstanding from the marginal portion of the leather sheet and constituting a sewing rib, a line of stitching passed through the leather and fabric sheets at the base of the sewing rib, and a limp leather sock lining at least no thicker than said leather sheet adhesively affixed to the forepart of said leather sheet over said stitching, said leather and fabric sheets in the flat innersole being free from tension and the sock lining being under tension.

3. A two-ply innersole consisting of adhesively and mechanically attached leather and fabric sheets characterized by ability to flex into a position wherein the forepart of the innersole is at right angles to the rear part with the leather sheet innermost without the formation of wrinkles on the inner face of the leather sheet, said leather sheet being uniformly thin throughout its extent and so thin that it cannot be channeled to form a useable sewing rib, said fabric sheet being adhesively affixed to the leather sheet except at the marginal forepart which is turned out and constitutes the sewing lip for the innersole, the inner face of the leather sheet being under tension and the outer face thereof and the fabric sheet being under compression when the innersole is flat, the leather sheet being thin and the inner face thereof being so close to the inextensible fabric sheet that the innersole can be flexed into the aforesaid condition without plac-

ing the inner face of the leather sheet under sufficient compression to cause wrinkling.

4. The method of making an innersole comprising the steps of providing a leather sheet of sole configuration too thin to be channeled to form a sewing rib thereon and a fabric backing sheet of sole configuration, superimposing the sheets one on the other, bending the superimposed sheets transversely of the innersole with the leather sheet on the inner side of the bend, adhesively securing them together while they are held in the said bent condition, and then stitching the two sheets together by a line of stitching passed through both sheets at the base of the sewing rib.

5. The method of making an innersole comprising a leather sheet having a thin leather sock lining on at least the forepart of the inner face thereof and a fabric sheet on and coextensive with the opposite face except at the forepart where the marginal portion of the fabric sheet outstands and constitutes a sewing lip, said method consisting in stitching together the leather and fabric sheets prior to the application of the sock lining by a line of stitching passed through both sheets at the base of the sewing lip, bending the sock lining and attached sheets while free from firm attachment to each other and adhesively firmly uniting the sock lining to the combined sheets which all are in bent condition.

6. A composite innersole comprising a plurality of superimposed flexible sheet elements each having uniform thickness throughout its extent, two of said sheet elements being combined at the forepart of the innersole and flexed transversely of the innersole, and there being cement securing said sheet elements together at the forepart and tending to maintain their said transversely flexed condition, whereby the exposed concave surface of one of said elements is in condition to be tensioned to a considerable extent when the composite innersole is brought to a flat condition, said composite innersole having a fabric lip stitched thereto around the margin of its forepart for attachment of the innersole to the upper and welt of a shoe.

7. A composite innersole comprising a flexible body sheet of uniform thickness and a fabric backing sheet combined and cemented together and stitched together around the margin of the forepart and shank regions, said cement and stitching tending to maintain the combined sheets in mutually flat condition, and a thin facing sheet for the exposed side of the body sheet, said facing sheet being applied and cemented to the body sheet with the cement tending to maintain them flexed transversely of the innersole with the exposed surface of the facing sheet concave, whereby in the flat condition of the composite innersole, said facing sheet is under considerable tension, and the marginal portions of said backing sheet outside of said marginal stitching being bent away from the body sheet to constitute an attaching lip for securement of the innersole in a shoe.

WILLIAM L. KNIPE.
